(57) **CLAIM**

The ornamental design for a golf club, as shown and described.

DESCRIPTION

FIG. 1 is a perspective view of a first embodiment of the golf club of the present invention;

FIG. 2 is a front view thereof;

FIG. 3 is a back view thereof;

FIG. 4 is a left side view thereof;

FIG. 5 is a right side view thereof;

FIG. 6 is a top view thereof; and

FIG. 7 is a bottom view thereof;

FIG. 8 is a perspective view of a second embodiment of the golf club of the present invention;

FIG. 9 is a front view thereof;

FIG. 10 is a back view thereof;

FIG. 11 is a left side view thereof;

FIG. 12 is a right side view thereof;

FIG. 13 is a top side view thereof;

FIG. 14 is a bottom side view thereof;

FIG. 15 is a perspective view of a third embodiment of the golf club of the present invention;

FIG. 16 is a front view thereof;

FIG. 17 is a back view thereof;

FIG. 18 is a left side view thereof;

FIG. 19 is a right side view thereof;

FIG. 20 is a top side view thereof; and,

FIG. 21 is a bottom side view thereof.

The dashed lines are for illustrative purposes only and form no part of the claimed ornamental design.
